R. E. FAIR

SHOCK ABSORBING ATTACHMENT FOR WELL CASINGS

Filed Oct. 4, 1919

Inventor,
Ralph E. Fair,
By G. Henderson,
Attest.

UNITED STATES PATENT OFFICE.

RALPH EMERSON FAIR, OF CHATTANOOGA, TENNESSEE, ASSIGNOR TO LUCEY MANUFACTURING CORPORATION OF TENNESSEE, OF CHATTANOOGA, TENNESSEE, A CORPORATION OF TENNESSEE.

SHOCK-ABSORBING ATTACHMENT FOR WELL CASINGS.

Application filed October 4, 1919. Serial No. 328,450.

To all whom it may concern:

Be it known that I, RALPH E. FAIR, a citizen of the United States, residing at Chattanooga, in the county of Hamilton and State of Tennessee, have invented certain new and useful Improvements in Shock-Absorbing Attachments for Well Casings; and I do declare the following to be a full, clear, and exact description of the invention, such as will enable others skilled in the art to which it appertains to make and use the same, reference being had to the accompanying drawings, and to the letters and figures of reference marked thereon, which form a part of this specification.

This invention relates to an improved resilient suspension device especially adapted for use in withdrawing the sectional pipe employed in drilling wells by the rotary process.

The principal objects are to provide a simply constructed and sturdy device which will have suitable shock absorbing properties, which will enable the pipe to be pulled out with greater speed and in a more facile manner, and which may be conveniently combined with the travelling block of the hoisting rig.

The invention consists in certain novel features of structure and combination which will be set forth as the description proceeds.

A device of preferred construction in which the features of the invention are incorporated is illustrated in the accompanying drawings, wherein:

Figure 1 is an elevation.

Figure 2 is a partial elevation taken at a right angle to the elevation of Figure 1 and also a partial vertical section.

Similar characters of reference designate corresponding parts in the two views.

The relatively movable parts are a cross head 1 and a stem 2 operating through a central opening in the cross head. At each side of the stem the cross head is supported by parallel hangers 3; these preferably project through openings in the cross head and at their lower ends are provided with nuts 4 or equivalent enlargements upon which the cross head rests. The hangers 3 are fashioned whereby they may be inserted in the travelling block, (not shown) that is to say between the parallel frame plates of

such block, in place of the shackle or bail which is usually employed. For this purpose said hangers at their upper ends project beyond the stem 2 when the latter is fully raised; and their projecting portions are formed with alined eyes 5 in which may be secured a cross pin 6 employed as a direct pivotal connection between said hangers and said block.

The stem 2 is acted on by one or more helical expansion springs 7; these surround the stem and exert their thrust against the cross head 1 and the end of a sleeve 8 within which they are partly housed when the stem is raised. The sleeve 8 is backed by a nut 9 secured upon the upper end of the stem and by its engagement with the cross head 1 limits the downward movement of the stem. Below the cross head the stem is formed with a collar 10 which, by its engagement with the cross head, limits the upward movement of the stem as effected by the springs 7. At its lower end the stem is pivotally connected to links 11 which take the place of the bail or shackle usually employed and carry the trunnion bar 12 of a swivelled hook 13 by which the device is connected to the pipe. For the connection of the links 11 the stem 2 is formed at its lower end and just below the collar 10 with an eye 14 in which is fitted a pin 15, the links being hung upon said pin and retained by collars 16 secured upon the ends of the pin.

The drill pipe as suspended by the device is pulled out by means of the hoisting rope and in such operation the springs 7 are fully compressed; that is to say the suspended load is greater than the intended capacity of the springs and the sleeve 8 therefore bears against the cross head 1. The operation of the hoisting rope is arrested as soon as a tool joint, by which adjacent sections of the pipe are connected, is brought above the floor of the derrick.

At such time the usual means, well known to those skilled in the art, is employed to hold the piping below the exposed tool joint in the position to which it has been raised and the elements of the joint are disconnected. As soon as the co-operating threads of such elements have been disengaged the springs 7 act to raise the section of pipe

above the tool joint; and the section thus raised carries with it the associated element of the tool joint, i. e., the tool joint pin, lifting it clear of the other elements, the tool joint box which is associated with the adjacent section of pipe still remaining in the well. Thus the springs 7 render it unnecessary to operate the twisting mechanism in order to lift the upper element of the tool joint clear of the lower element and it follows that a substantial saving of time and work is effected.

Having fully described my invention I claim:

- 15 1. In a device of the type set forth the combination of a pair of hangers, a cross bar supported at their lower ends, a stem movable through the cross bar between the hangers, a sleeve having a bearing against the upper end of the stem and terminating short of the cross bar, a helical expansion spring exerting its thrust against the cross bar and the end of the sleeve, the stem having below the cross bar a collar which engages the cross bar to limit the upward movement of the stem and having an eye below said collar, a pin fitted in said eye, and hook-supporting links hung from said pin.
- 20 2. In a device of the type set forth the combination of a pair of hangers, a cross bar supported at their lower ends, a stem movable through the cross bar between the hangers, a sleeve having a bearing against the upper end of the stem and terminating short of the cross bar, a helical expansion spring exerting its thrust against the cross bar and the end of the sleeve, the stem having below the cross bar a collar which engages the cross bar to limit the upward movement of the stem and having an eye below said collar, a pin fitted in said eye, and hook-supporting links hung from said pin, said hangers having their upper ends formed for insertion into a travelling block and provided with aligned eyes located above said stem when in its fully raised position.
- 25 3. In a device of the type set forth the combination of a pair of hangers, a cross bar supported at their lower ends, a stem movable through the cross bar between the hangers, a sleeve having a bearing against the upper end of the stem and terminating short of the cross bar, a helical expansion spring exerting its thrust against the cross bar and the end of the sleeve, the stem having below the cross bar a collar which engages the cross bar to limit the upward movement of the stem and having an eye below said collar, a pin fitted in said eye, and hook-supporting links hung from said pin, said hangers having their upper ends formed for insertion into a travelling block and provided with aligned eyes located above said stem when in its fully raised position.

In testimony whereof I affix my signature in presence of two witnesses.

RALPH EMERSON FAIR.
